UNITED STATES PATENT OFFICE.

TOBIAS BÄUERLE, OF ST. GEORGEN, GERMANY.

DRIVE FOR WEIGHT-MOVED CLOCKS.

1,408,718.

Specification of Letters Patent.

Patented Mar. 7, 1922.

Application filed October 24, 1921. Serial No. 510,115.

To all whom it may concern:

Be it known that I, TOBIAS BÄUERLE, a citizen of the German Republic, residing at St. Georgen, Germany, have invented certain new and useful Improvements in Drives for Weight-Moved Clocks, of which the following is a specification.

With spring-moved clocks it has already become known to drive by means of the spring barrel the clockwork as well as the striking mechanism. For weight-moved clocks it has however not yet been possible to use the weight barrel for the two purposes.

15 This object has been attained by the present invention according to which an auxiliary axle is arranged in the weight barrel keyed upon its shaft, said auxiliary axle carrying two drive wheels outside the side walls of the barrel, one of said wheels meshing with the inner teeth of a drive wheel loosely mounted upon the shaft of the barrel (designed for instance to drive the clockwork), the other wheel meshing with a 20 toothed wheel loosely mounted upon the shaft of the barrel (designed for instance to drive the striking mechanism).

25 This arrangement permits to drive both mechanisms either simultaneously or separately from the weight barrel.

30 In order that the invention may be clearly understood, I shall proceed to describe the same with reference to the form of construction shown by way of example on the accompanying drawing, wherein:—

35 Fig. 1 shows the weight barrel in a longitudinal section.

Fig. 2 is a side elevation of Fig. 1.

The weight barrel *a* is keyed upon the 40 shaft *b*. In the side walls *c* of the barrel a small axle *d* is mounted so that it can freely revolve. Upon the ends of this axle *d*, outside the side walls *c*, a pinion *e* and a pinion *f* are keyed. The pinion *f* meshes 45 with the inner teeth *g* of a toothed wheel *h* loosely mounted upon the shaft *b* of the barrel, said toothed wheel serving for instance to drive the clockwork mechanism. The pinion *e* is in gear with a toothed wheel 50 *i* fixed to a ratchet wheel *k* and loosely mounted with said ratchet upon the shaft *b*. The pawl *m* for the ratchet *k* is pivoted upon a disk *n* loosely mounted upon the shaft *b*, and designed to act upon a driver *p* of a

55 toothed wheel *o* which is loosely mounted on shaft *b*. The driver *p* is fixed upon a ring *q* which is inserted in the toothed wheel *o*, said toothed wheel serving for instance to operate the striking mechanism. The parts loosely mounted upon the shaft *b* are secured in their positions by two disks *r*, *s* which are secured themselves by pins *t*, *u*.

60 The device operates differently according to whether neither the clockwork nor the striking mechanism are braked against the revolving motion transmitted from the shaft *a* of the barrel through the action of the weight or whether one of said mechanisms is braked. In the first case the barrel *a* revolves by means of the pinions *e*, *f*, which 65 however are not revolved individually, all the driving parts of the two mechanisms. When the clockwork mechanism is braked the pinion *f* rolls along the inner teeth *g* of the driving wheel *h* for the clockwork 70 mechanism. The individual revolving movement of the axle *d* which is thus produced operates the striking mechanism by means of the pinion *e*. If however the striking mechanism or its driving wheel *o* is braked 75 only the clockwork mechanism is operated through the intermediary of pinion *f* and the inner teeth *g*, owing to the revolving of the pinion *e* caused by toothed wheel *i*. The two 80 mechanisms can therefore be operated either 85 simultaneously or separately.

A separate drive could be provided for the striking mechanism or for the striking mechanisms, in which case the weight barrel for the clockwork mechanism could be 90 used as auxiliary drive for the striking mechanism.

I claim:—

1. An improved drive for weight-moved 95 clocks comprising in combination with the weight-moved barrel, the clockwork mechanism and another mechanism (for instance a striking mechanism) and means for operating said two mechanisms from said weight-barrel.

100 2. An improved drive for weight-moved clocks comprising in combination with the weight-moved barrel, the clockwork mechanism and another mechanism (for instance a striking mechanism), a small axle revolvably mounted in said weight-barrel so that its ends project over said barrel, two pinions 105 loosely mounted one upon each projecting

end of said axle, a toothed wheel loosely mounted upon the barrel shaft for driving the clockwork mechanism having inner teeth with which one of said pinions is in gear, a 5 second toothed wheel loosely mounted upon the shaft of the weight-barrel in gear with the other pinion, a driving wheel for the second mechanism, and means for revolving

said driving wheel from said second toothed wheel.

In testimony whereof I affix my signature in presence of two witnesses.

TOBIAS BÄUERLE.
